CLAIM

The ornamental design for a power strip, as shown and described.

DESCRIPTION

FIG. 1 is a perspective view of a power strip having outlets on three sides according to the present invention, the broken lines are shown for illustrative purposes only and form no part of the claimed design;

FIG. 2 is a front elevational view of the power strip of FIG. 1; and,

FIG. 3 is a left elevational view of the power strip of FIG. 1, the right elevational view being a mirror image thereof. The surface(s) or portion(s) of the article not shown in the drawings or described in the specification form(s) no part of the claimed design.
